(57) **CLAIM**

The ornamental design for a boot upper pattern, as shown and described.

DESCRIPTION

FIG. 1 is a perspective view of the boot upper pattern illustrated with a lace cover thereof in a closed position; FIG. 2 is a front elevational view of the boot upper pattern; FIG. 3 is a rear elevational view of the boot upper pattern; FIG. 4 is an elevational view of one side of the boot upper pattern;

FIG. 5 is an elevational view of another side of the boot upper pattern;

FIG. 6 is a top plan view of the boot upper pattern; and, FIG. 7 is a perspective view of the boot upper pattern illustrated with the lace cover thereof in an open position. In FIGS. 1-7, the outsole, laces, and heel loop shown in broken lines do not form any part of the claimed design.
